CLAIM

(30) **Foreign Application Priority Data**

The ornamental design for an external hard disk box, as shown and described.

Apr. 6, 2007 (CN) 2007 3 0200241

DESCRIPTION

(51) **LOC (8) Cl.** **14-02**

FIG. 1 is a perspective view of an external hard disk box showing our new design;

(52) **U.S. Cl.** **D14/363**

FIG. 2 is a front elevational view thereof;

(58) **Field of Classification Search** D13/149,

FIG. 3 is a back elevational view thereof;

D13/184; D14/356-369; 360/131-133,

FIG. 4 is a left-side, elevational view thereof;

360/97.01, 97.03; 361/683-686, 724-725,

FIG. 5 is a right-side, elevational view thereof;

361/752; 369/272.1, 273, 75.11, 13.01; 711/100,

FIG. 6 is a top plan view thereof; and,

711/115

FIG. 7 is a bottom plan view thereof.

See application file for complete search history.
